UNITED STATES PATENT OFFICE

CHARLES L. WATERSTON, OF NASHVILLE, TENNESSEE, ASSIGNOR OF ONE-HALF TO
DAVID J. KENNEDY, OF NASHVILLE, TENNESSEE

PROOF PRESS

Application filed June 25, 1928. Serial No. 288,030.

This invention relates to a proof printing press, the general object of the invention being to provide means whereby proofs can be easily and quickly printed from type forms and in a clear manner and without touching the paper until the proof is printed, with means for carrying a roll of paper on the paper carrying member, thereby eliminating loss of paper through careless handling and placing of the paper in piles adjacent the press.

Another object of the invention is to provide automatic means for lowering the paper carrying member so as to place the paper on the type at the beginning of the printing operation and for raising the member at the end of the operation so that the paper is automatically placed on the type and removed therefrom during the operation of the press.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of the improved press.

Figure 2 is a view of the opposite side.

Figure 3 is a view of one end of the press.

Figure 4 is a view of the other end.

Figure 5 is a section on line 5—5 of Figure 3, showing the parts with the half cylinder in raised position.

Figure 6 is a similar view, but showing the half cylinder in lowered position.

Figure 7 is a section on line 7—7 of Figure 5.

Figure 8 is a sectional detail view showing one of the spring pressed rollers for holding the paper against the knife and on the half cylinder.

In these views, the numeral 1 indicates a table which is provided with a flat surface

to receive the pipe A shown in dotted lines in Figure 3 and with the racks 2 at the sides thereof. Upright frames 3 are fastened to the sides of the table and these frames are formed with the guideways 4. The paper to be printed upon is carried by a semi-circular cylinder 5 which is fastened to a shaft 6, the ends of the shaft passing through the eccentric members 7, which carry the rings 8 for engaging the guideways 4, the rings being supported on the eccentrics by the roller bearings 9. Each eccentric is formed with a flange 10 which abuts the outer face of each frame 3 and overlaps the guideways and the outer end of each eccentric is formed with a friction head 11 which extends into a recess 12 formed in a hub 13 fastened to each end of the shaft, one hub forming a part of the hand wheel 14. A friction ring 15 is fastened to each hub by the bolts 16 in such a manner that the head 11 is frictionally held between the hub and the ring. The ends of the half cylinder 5 are formed with the rack teeth 17 which engage the rack bars 2 and a roll of paper B is carried by a shaft 18 detachably connected with the rear part of the half cylinder, as shown at 19, adjacent the top thereof so that portions of the paper can be passed over the half cylinder, the paper being held on the half cylinder by the rolls 20, the stems of which are pressed by the springs 21 so that the rolls press the paper against a knife bar 22 at the lower end of the half cylinder and thus hold the paper on the half cylinder.

Each flange 10 is formed with a forward extension 10' which carries a small roll 23 adjacent its free end for engaging either the upper or lower bar of the guideway 4.

A portion of the paper is pulled from the roll B and passed over the half cylinder and between the rolls 20 and the knife bar 22, so that a portion of the paper is stretched over the curved surface of the half cylinder, it being understood that suitable packing is placed between the curved surface and the paper. Then the type form is placed on the table and inked and then the hand wheel is turned. The inward movement of the hand wheel will cause the friction means to turn

the eccentric 7 on the ends of the shaft 6 so that the shaft and the half cylinder will be lowered to place the cylinder and the paper thereon against the form. When the rollers 5 23 on the extensions 10' of the flanges 10 of the eccentrics engage the lower bars of the guideways, further movement of the eccentrics will be prevented and then the turning movement of the hand wheel will cause the eccentrics, together with the shaft and the half cylinder to roll toward the rear ends of the guideways and thereby cause the paper on the half cylinder to contact with type and thus the paper will be printed. When the 10 half cylinder reaches the end of the form, the wheel is turned in an opposite direction, the initial movement of the wheel turning the eccentrics so that the shaft and the half cylinder are moved upwardly, whereby the paper 15 is lifted above the type and as soon as the rollers 23 strike the upper bars of the guideways 4, further upward movement of the parts is prevented and then the continued movement of the hand wheel causes the parts 20 to pass to the front of the machine to their original positions. The free end of the paper is then uppermost and the end of the paper is seized between the fingers and the paper pulled outwardly until the printed portion 25 passes the knife bar 22, when the paper can be severed by pulling it against the corner of the knife bar so that the printed portion can be severed from the rest of the paper. This action of removing the printed portion 30 will place a new portion of the paper on the half cylinder. As will be seen, during the movement of the hand wheel, the teeth on the half cylinder will engage the rack bars 2 so that the half cylinder is prevented from slipping 35 and thereby prevent blurring of the printing by the drag of the paper on the type.

The half cylinder provides a nearly flat printing surface during the printing operation, thereby insuring clear print and the 40 half cylinder is automatically lowered at the beginning of the printing operation to place the paper upon the type and is automatically raised at the end of the operation to raise the paper above the type, thus not only insuring clear print, but preventing inking of the 45 packing. By having the roll of proof paper on the half cylinder, a saving of paper and time results and a better and cleaner proof is secured as the paper is drawn tight over the 50 cylinder and is not touched until the printing is completed. Furthermore, there is no necessity of having the paper arranged in piles adjacent the press, as the paper is carried directly on the half cylinder.

60 It is thought from the foregoing description that the advantages and novel features of my invention will be readily apparent.

It is to be understood that I may make 65 changes in the construction and in the combination and arrangement of the several parts,

provided that such changes fall within the scope of the appended claims.

What I claim is:—

1. A proof printing press comprising a table, guiding means at the sides of the table above the same, rack bars at the sides of the table, a shaft passing through the guiding means, rolls carried by the shaft engaging the guideways, a half cylinder carried by the shaft, means for supporting a roll of paper on the half cylinder, means for holding a portion of the paper on the curved surface of the half cylinder, a handle attached to the shaft for rotating the same to cause it to travel from one end of the guiding means to the other, a knife bar carried by the half cylinder for cutting the paper after the same has been printed and the printed portion pulled over the curved surface to a point where the knife will sever the printed portion, thus leaving a new portion of the paper on the half cylinder and automatic means for lowering the half cylinder and its shaft at the beginning of the printing operation and raising the half cylinder and its shaft at the end of the printing operation. 70 75 80 85 90

2. A proof printing press comprising a table, guiding means at the sides of the table above the same, rack bars at the sides of the table, a shaft passing through the guiding means, rolls carried by the shaft engaging the guideways, a half cylinder carried by the shaft, means for supporting a roll of paper on the half cylinder, means for holding a portion of the paper on the curved surface of the half cylinder, a handle attached to the shaft for rotating the same to cause it to travel from one end of the guiding means to the other, a knife bar carried by the half cylinder for cutting the paper after the same has been printed and the printed portion pulled over the curved surface to a point where the knife will sever the printed portion, thus leaving a new portion of the paper on the cylinder, automatic means for lowering the half cylinder and its shaft at the beginning of the printing operation and raising the half cylinder and its shaft at the end of the printing operation, such means comprising eccentrics on the shaft and carrying the rolls which engage the guideways and frictional means for connecting the eccentrics with the shaft. 95 100 105 110 115

3. A proof printing press comprising a table, guiding means at the sides of the table above the same, rack bars at the sides of the table, a shaft passing through the guiding means, rolls carried by the shaft engaging the guideways, a half cylinder carried by the shaft, means for supporting a roll of paper on the half cylinder, means for holding a portion of the paper on the curved surface of the half cylinder, a handle attached to the shaft for rotating the same to cause it to travel from one end of the guiding means to the other, a knife bar carried by the half cylinder 120 125 130

for cutting the paper after the same has been printed and the printed portion pulled over the curved surface to a point where the knife will sever the printed portion, thus leaving a new portion of the paper on the cylinder, automatic means for lowering the half cylinder and its shaft at the beginning of the printing operation and raising the half cylinder and its shaft at the end of the printing operation,
5 such means comprising eccentrics on the shaft and carrying the rolls which engage the guideways, frictional means for connecting the eccentrics with the shaft and means for limiting the movement of the eccentrics by
10 the guiding means.
15 In testimony whereof I affix my signature.

CHARLES L. WATERSTON.
